CONTAINER**

Albert E. Bowen, Jr., Old Greenwich, Conn., assignor to
Alpha Molykote Corporation, Stamford, Conn.
Filed May 16, 1960, Ser. No. 29,242
4 Claims. (Cl. 15—521.5)

This invention relates to a container, and relates in particular to a container having applicator means associated therewith.

In dispensing certain solid, liquid, gelled, and any combination thereof, substances from a container, it is often desirable to prevent contamination of such materials in their container by the applicator used in applying the materials to the work at hand. Similarly, it is desirable not to contaminate the work to which the substance is being applied with any foreign matter. One convenient method of achieving this is by applying the substance to the work with an applicator used only with said substance. In such a case, it is critical that the applicator be maintained in an uncontaminated condition during and between use.

For example, in the application of specialty lubricants to parts to be lubricated, it is desirable to maintain the lubricant free of any grit, metal filings, or other foreign matter which would interfere with the properties of the lubricant. Similarly, it is desirable to apply the lubricant, and nothing but the lubricant, to the work to be lubricated. Contamination of either the source or the work is to be avoided. This is conveniently accomplished by applying the lubricant with a special applicator used only with that lubricant, and by maintaining the applicator in a clean condition between use.

The present invention relates to a container having integrally associated therewith an applicator which is conveniently stored with the materials with which it is used, but yet is stored out of contact with the materials, facilitating the maintenance of the applicator in an uncontaminated condition at all times. This end is achieved according to the present invention by incorporating the applicator in the lid of the container, and by providing a special well within the container for separate storage of the applicator, when the container is sealed, out of contact with the other contents of the container. Such a device is of particular advantage when employed with specialty greases and lubricants, because the applicator used to apply these lubricants can be maintained in an uncontaminated condition between uses. Also, the applicator can be associated exclusively with the same lubricant, and is so stored as to minimize contamination of either the lubricant or the work lubricated with harmful foreign matter.

A better understanding of the invention and of its many advantages can be had by reference to the accompanying drawings showing a preferred embodiment of the invention by way of example. In the drawings, FIGURE 1 is a side elevation in section of a sealed container device according to the present invention;

FIGURE 2 is a plan view of said sealed container; and

FIGURE 3 is an exploded view of a portion of the lid assembly of said container.

Referring to FIGURE 1 of the drawings, the figure shows cylindrical receptacle or container body 11 of a sturdy material such as metal or plastic, conveniently medium impact polystyrene. Centrally positioned within said container is second receptacle or well 12, also of a rigid material such as metal or plastic, conveniently polystyrene. Well 12 is advantageously affixed at its bottom portions 13 to container body 11 by any convenient means such as gluing, soldering, heat sealing, etc. The upper portions of container 11 have threaded portions 14 to receive flat lid 15 having matching threaded

2

portions 14. Lid 15 is also conveniently made of a sturdy shock-resistant substance such as metal or plastic.

Mounted within lid 15 are applicator means comprising brush 16 which may be of a natural fiber or of a synthetic fiber such as crimped nylon, slideable ferrule 17, conveniently of metal, and wire member 18. Brush 16 is affixed to one terminus of wire member 18, conveniently by pinching brush 16 in a twisted portion of member 18, as suggested by the figure. Wire member 18 terminates in its upper portion in a circular wire loop 19 peripherally mounted within lid 15. Lid 15 has been molded, pressed, swaged, or otherwise worked to flare in its peripheral portions to provide a slot extending around the periphery of lid 15 for reception of circular wire loop 19. The diameter of lid 15 in the region of this peripheral slot is greater than its diameter at threaded portion 14, permitting a tight seal of receptacle 11 without interference from loop 19 in lid 15.

Within lid 15 is lid liner 20, which may be of any sturdy, flexible material resistant to the contents of container 11, and conveniently may be of vinyl-coated paper, for example. When lid 15 is screwed onto container 11, liner 20 is pressed tightly to the upper lip of container 11, and provides a tight seal thereto. Centrally affixed to the under side of said liner 20 is washer or gasket 21 which provides a seal to well 12 when container 11 is sealed. Washer 21 is conveniently made of a compressible material resistant to the contents of the container, such as closed pore synthetic rubber, and is affixed to lid liner 20 by gluing, for example. Washer 21 seals well 12 from the remaining interior portions of container body 11, so that the liquid, solid, gelled or any combination thereof contents stored in annular cavity 22 within container body 11 are prevented from passing into well 12 in which the applicator means are stored. Liner 20 and washer 21 are centrally pierced to provide passage therethrough for wire member 18.

Flat lid 15 also is provided with one or more central embossed portions 23, which are depressed below the upper surface of lid 15 to an extent approximately equal to the thickness of circular wire loop 19. These embossed portions 23 provide support for liner 20, which may be affixed thereto by gluing or other suitable adhesives. Alternatively, liner 20 may simply be held within lid 15 by a compression fit in the neck thereof between threaded portion 14 of lid 15 and the peripheral slot formed in said lid to hold circular wire loop 19, or may rest in said peripheral slot itself.

FIGURE 2 is a plan view of the container in FIGURE 50 1 showing lid 15, having embossed portions 23, and its relationship to circular wire loop 19 (dotted lines), and centrally positioned well 12 (dotted lines).

FIGURE 3 is an exploded view of a portion of the lid assembly or sealing means showing lid 15 having embossed 55 portions 23, wire member 18 terminating in circular wire loop 19, lid liner 20, and sealing washer 21 (dotted lines) associated therewith.

The container embodiment just described will be seen to have a number of advantages. Thus, it provides for 60 separate but integral storage of a material and an applicator therefor without the possibility of contamination of either. The applicator, if cleaned between uses, is stored in clean condition for the next use. The container-applicator combination reduces or eliminates the soiling of hands or clothing, and is especially useful where materials such as greases or lubricants are to be employed.

By simple inversion of the flat lid of the container, when it is removed from the container, the applicator can be conveniently set aside without contamination if 70 it is desired not to return it immediately to the container. The flat lid provides a broad base support for the brush, which extends up into the air without possibility of con-

tamination by contact with foreign matter on a work bench or the like.

The container may be made in a variety of sizes adapted to fill any equally wide variety of needs. It can be made of shock-resistant materials, and of materials resistant to acids, alkalies, greases, and the like, depending on its contents and the conditions under which it will be used.

Also, in the container combination, the applicator is made integral with the container lid assembly. The large looped base of the brush, securely locked within the lid, permits the use of the applicator with substantial force and pressure without the development of a torque sufficient to dislodge the brush from the lid.

Further, the slideable ferrule in the applicator assembly facilitates cleaning of the entire brush when desired, and yet provides a sturdy mounting for the bristles of the brush at their base.

Although specific embodiments have been shown and described, it is to be understood that they are illustrative, and are not to be construed as limiting on the scope and spirit of the invention.

What is claimed is:

1. A container for greases, lubricants, and the like comprising a first receptacle; a second receptacle centrally positioned within said first receptacle, whereby a volume for the contents of said container is defined between said first and second receptacles; sealing means adapted to be sealably affixed to said first receptacle, said sealing means comprising a flat lid embossed in central portions to define a plurality of depressed portions and a raised groove therebetween; and applicator means affixed to said sealing means and non-rotatably engaged in said raised groove and extending into said second receptacle when said sealing means are in sealing position, whereby said applicator means are separately stored in said second receptacle out of contact with said contents of said container in said first receptacle.

2. A container for greases, lubricants, and the like comprising a first receptacle; a second receptacle centrally positioned within and affixed to said first receptacle, whereby a volume for the contents of said container is defined between said first and second receptacles; sealing means adapted to be sealably affixed to said first receptacle, said sealing means comprising a flat lid flared in peripheral portions and embossed in central portions thereof to define a plurality of depressed portions and a raised groove

therebetween, a liner positioned in said lid and supported by said embossed central portions of said lid, and a washer centrally affixed to said liner and adapted to seal said second receptacle; and applicator means comprising a wire member having a loop portion positioned within said flared peripheral portions of said lid, a first straight portion coplanar with said loop portion and non-rotatably engaged in said raised groove, and a second straight portion extending centrally through said liner and washer, and applicator means attached to said second straight portion of said wire member.

3. In combination, a double walled container comprising a bottom, an outer wall, and an inner wall defining among them an annular cavity between said outer and inner wall for reception of the contents of said container and a central well within said inner wall; sealing means comprising a flat lid adapted to be sealably affixed to said container at its outer wall and a washer centrally affixed to said lid and adapted to seal separately said central well, said lid comprising depressed portions defining a raised groove therebetween, and applicator means centrally affixed to said lid and non-rotatably engaged with said raised groove therein and extending from said washer; whereby said applicator means extend into said central well when said sealing means are in sealing position, said applicator means thus being separately stored in said central well out of contact with said contents of said annular cavity.

4. A combination as in claim 3 wherein said applicator means comprise a wire member having a loop portion peripherally affixed to said lid of said sealing member and a first straight portion, coplanar with said loop portion, which first straight portion is non-rotatably engaged in said raised groove, as a first terminus and a second straight portion as a second terminus, and a brush affixed to said straight portion of said wire member.
